UNITED STATES PATENT OFFICE.

RALPH N. HILL, OF MONTCLAIR, NEW JERSEY, ASSIGNOR TO WESTERN ELECTRIC COMPANY, OF NEW YORK, N. Y., A CORPORATION OF ILLINOIS.

SELECTIVE SIGNALING SYSTEM.

1,103,583.

Specification of Letters Patent. Patented July 14, 1914.

Application filed March 21, 1912. Serial No. 685,241.

To all whom it may concern:

Be it known that I, RALPH N. HILL, citizen of the United States, residing at Montclair, in the county of Essex and State of New Jersey, have invented a certain new and useful Improvement in Selective Signaling Systems, of which the following is a full, clear, concise, and exact description.

This invention relates to party line selective signaling systems for train despatching or like purposes, in which a plurality of way stations located upon a line are selectively signaled from a main or sending station.

The object of this invention is to provide an efficient, convenient and reliable means for signaling the main or sending station from any one of the way stations.

In a system to which this invention is particularly adaptable the way station selectors are bridged across the line and an impulse-sending relay, located at the main or sending station, is operated to intermittently connect a source of current to the line wires for operating the selectors. In the application of this invention to this system the apparatus is so combined and connected that the operation of a circuit-closing device at any one of the waystations will cause the operation of the impulse relay which will close a circuit for a local signal located at the main or sending station. Means is provided at the sending station for interrupting the operation of the local signal, said means comprising apparatus-connecting devices which are included in the circuits of the signal and the impulse relay, and are operated by the connection and disconnection of a despatcher's telephone set with the line wires. Means is also provided for maintaining the signal circuit closed after the release of the circuit-closing device at the waystation, said means consisting in the provision of a locking circuit for the impulse relay which includes contacts on the apparatus-connecting devices which are opened by the connection of the despatcher's telephone set with the line wires.

The drawing illustrates schematically the apparatus and wiring of a system embodying this invention.

In said drawing, A designates a sending or despatching station connected by means of line wires 5 and 6 with waystations B and C. Located at the sending station is a battery 7 and an impulse relay 8 adapted

when operated to close contact levers 9 and 10 to send impulses from said battery over the line wires, as will be more fully described hereinafter. Also located at the sending station are jacks 12 and 13 adapted to receive plugs 14 and 15 with which are connected a telephone set. The sleeve contact of the jack 12 is connected through the secondary of an induction coil 16 and a protector 17 with the line wire 6, while the sleeve contact of the jack 13 is connected through a condenser 18 and a protector 19 with the line wire 5. The tip springs of the jacks 12 and 13 are adapted to be connected together through the primary of the induction coil 16 and a local battery 20. The tip contacts of the plugs 14 and 15 are connected with a telephone transmitter 25, and the sleeve contacts of said plugs are connected with a receiver 26. Thus, when the plugs 14 and 15 are inserted in the jacks 12 and 13, the receiver 26 is bridged across the line wires 5 and 6 in series with the condenser 18 and the secondary of the induction coil 16, while the transmitter is in a local circuit 75 with the battery 20 and the primary of the induction coil 16, which local circuit is controlled by a key 27. Contacts 30 and 31 are closed on the jacks 12 and 13 when the plugs 14 and 15 are removed, and opened when 85 said plugs are inserted. A local signal 35 has a circuit including the contacts of the jack 12 and the battery 7, and a locking winding 36 for said relay 8 is also in a circuit with said battery 7 adapted to be closed 90 through the contacts on the jack 12.

Located at each of the waystations is a selector mechanism comprising electromagnets 40 and 41 connected in series and in bridge of the line wires 5 and 6, and responsive to current impulses from the sending station to operate a circuit-closing member 42 adapted to bridge an electromagnet 43 across the line wires. The operation of the electromagnet 43 may operate any suitable 100 signal. Also bridged across the line wires at each of the waystations is a telephone set 45 having answer-back means associated therewith, but this forms no part of the present invention and need not be more 105 fully described herein. A key 50 located at each of said waystations is adapted when operated to connect ground to the two line wires for the purpose of operating the relay 8 at the sending station for signaling the 110

despatcher at that station, as will be more fully described.

As shown in the drawing, the battery 7 is adapted to be connected with line wires 5 and 6 through retardation coils 51, 52 and 53, which coils act in conjunction with a condenser 54 bridged across the line to smooth out or graduate the selecting impulses in order that no disagreeable click or thump will be heard in receivers which may be on the line during a signaling operation. A bridge including a non-inductive resistance 55 normally closed across the line at the sending station is adapted to be intermittently opened by the operation of the contact levers 9 and 10 of the impulse relay 8, said non-inductive resistance serving as a temporary discharge path for the graduating devices to prevent the sticking 20 of the selector magnets.

Referring now to the operation for signaling the despatcher from one of the waystations, it will be assumed that the despatcher has withdrawn the plugs 14 and 15 25 from the jacks 12 and 13, thus closing contacts 30 and 31. The depression of the waystation key 50 will close contacts 60 and 61 to complete an energizing circuit for the impulse relay 8 at the sending station. This 30 circuit will comprise two current paths, one of which may be traced as follows: from ground 62 at the waystation through resistance 63, contact 61 of the key 50, resistance 65, conductor 66, conductor 67, arrester 68, conductor 69, line wire 6, retardation coil 53, one-half retardation coil 51, battery 7, other half of retardation coil 51, conductor 70, energizing winding of impulse relay 8, conductor 71, contact 72, conductor 73, and contacts 31 on jack 13, to ground at 74. The other of said paths may 40 be traced from ground 62, resistance 63, contact 60, resistance 75, conductor 76, conductor 77, arrester 78, conductor 79, line 45 wire 5, retardation coil 52, contact lever 10, contact 80, non-inductive resistance 55, conductor 81, one-half of retardation coil 51, battery 7, other half of retardation coil 51, conductor 70, energizing winding of impulse 50 relay 8, conductor 71, contact 72, conductor 73, and contacts 31 on jack 13, to ground at 74. The current in these two paths energizes the impulse relay 8 to close contact between levers 9 and 10, and open 55 the contact 80, thus connecting the battery 7 with the line wires and interrupting one of the paths for current previously traced. Two current paths are provided at the sending station, one being through the signal 35, 60 the other being through the locking winding 36 of the impulse relay. The path for the current through the signal 35 may be traced as follows:—from one side of the battery 7, through one-half of the retardation coil 51, contact levers 9 and 10, line

conductor 5 to conductor 85, armature of signal 35, winding of said signal, conductor 86, conductor 87, contacts 30 of jack 12, conductor 88 to line wire 6, retardation coil 53, the other half of retardation coil 51 to the 70 other side of the battery 7. The path for the current through the locking winding 36 of the relay 8 may be traced as follows:—from one side of the battery 7, through half of retardation coil 51, contact levers 9 and 10, line conductor 5, retardation coil 52, conductor 85, conductor 90, through locking winding 36, conductor 91, conductor 87, contacts 30 of jack 12, conductor 88, to line 75 wire 6, retardation coil 53, the other half of retardation coil 51, to the other side of the battery 7. The insertion of the plug 14 into the jack 12 will interrupt both of these circuits at the contacts 30, stop the ringing of the bell, and connect the telephone set with the line wires.

I claim:—

1. In a selective signaling system the combination with line wires having a sending station and a plurality of waystations connected therewith, of impulse transmitting means at said sending station including an impulse relay for transmitting signaling impulses over said line wires, apparatus connecting devices at said sending station, a circuit-closing device at each of said waystations, an operating circuit for said impulse relay including said circuit-closing devices and contacts on said apparatus connecting devices, a local signal and a circuit 90 therefor closed by said impulse relay and including contacts on said apparatus connecting devices.

2. In a selective signaling system the combination with line wires having a sending 105 station and a plurality of waystations connected therewith, of impulse-transmitting means at said sending station including an impulse relay, circuit-closing means and connections for operating said relay from any one of said waystations, a signal at the sending station adapted to be controlled by the operation of said impulse relay, and means for maintaining said relay operated after the release of the circuit-closing means 110 at the waystation.

3. In a selective signaling system the combination with line wires having a sending station and a plurality of waystations connected therewith, of impulse-transmitting 120 means at said sending station including an impulse relay, circuit-closing means and connections for operating said relay from any one of said waystations, a signal at the sending station adapted to be controlled by 125 said impulse relay, and a locking circuit for said impulse relay adapted to be closed thereby.

4. In a selective signaling system the combination with line wires having a sending 130

station and a plurality of waystations connected therewith, of impulse-transmitting means at said sending station including an impulse relay, circuit-closing means and 5 connections for operating said relay from any one of said waystations, a signal at the sending station adapted to be controlled by said impulse relay, a holding circuit for maintaining said relay energized after the 10 release of the circuit-closing means at the waystation, and means at the sending station for interrupting said holding circuit.

5. In a selective signaling system the combination with line wires having a sending 15 station and a plurality of waystations connected therewith, of impulse-transmitting means at said sending station including an impulse relay, circuit-closing means and connections for operating said relay from 20 any one of said waystations, a signal at said sending station adapted to be controlled by said impulse relay, a holding circuit for maintaining said relay energized after the release of the circuit-closing means at the 25 waystation, a telephone set adapted to be connected with the line wires at the sending station, and means operated in the connection of said telephone set to the line wires for releasing said impulse relay.

30 6. In a selective signaling system the combination with line wires having a sending station and a plurality of waystations connected therewith, of impulse transmitting means including an impulse relay, circuit- 35 closing means and connections for operating said relay from any one of said waystations, a signal at said sending station adapted to be controlled by the operation of said impulse relay, a holding circuit for maintain-

ing said relay energized after the release of 40 the circuit-closing devices at the waystation, a telephone set, plugs and jacks for connecting said set with said line wires at the sending station, and contacts on one of said jacks in the circuit of said locking winding, said 45 contacts being controlled in the insertion and withdrawal of the plugs.

7. In a selective signaling system the combination with line wires having a sending station and a plurality of waystations connected therewith, impulse-transmitting apparatus at said sending station including an impulse relay, a source of current at said sending station, a signal at said sending station, a telephone set, jacks and plugs for 50 connecting said telephone set with said line wires, contacts on said jacks controlled in the insertion and withdrawal of said plugs, circuit-closing devices and connections for operating said impulse relay from any one 55 of said waystations, said connections including the line wires said source of energy and contacts on one of said jacks, an operating circuit for said local signal controlled by the operation of said impulse relay and including said source of energy and the contacts of the other of said jacks, and a locking circuit for said impulse relay also including said source of energy and the contacts on said second named jack.

In witness whereof, I hereunto subscribe my name this 16th day of March A. D., 1912.

RALPH N. HILL.
